Inventor:
William Reddall.

UNITED STATES PATENT OFFICE.

WILLIAM REDDALL, OF 10 SOUTH STREET, FINSBURY, COUNTY OF MIDDLESEX, ENGLAND.

STREET-CURB.

SPECIFICATION forming part of Letters Patent No. 249,400, dated November 8, 1881.

Application filed June 30, 1881. (No model.)

To all whom it may concern:

Be it known that I, WILLIAM REDDALL, a subject of the Queen of Great Britain, residing at 10 South street, Finsbury, in the county 5 of Middlesex, England, have invented an Improved Street-Curb, of which the following is a specification.

This invention has for its object an improved street-curb.

10 The improved curb, when it is raised, forms, as usual, the edge of the raised footway and separates the footway from the road. It serves also (and this is the important feature in the invention) to contain telegraph-wires and other 15 wires for the conveyance of electricity.

The improved curbing is of cast-iron, and is made in sections, which are laid end to end. Each section has two members. The lower members are rectangular and of trough-like 20 form, and the upper members are flat and form covers to the lower sections. When the curbing is laid the covers are at the level of the footway, of which, indeed, they form a part. The covers have studs upon them, which enter 25 holes provided in the lower or trough-like members and serve both to connect these members end to end and to retain the covers in place. The wires are laid and inclosed in the interior of the curb.

30 In order that my said invention may be most fully understood and readily carried into effect, I will proceed to describe the drawings hereunto annexed.

In the drawings, Figure 1 is an elevation. 35 Fig. 2 is a plan. Fig. 3 is a longitudinal section, and Fig. 4 is a transverse section.

The curb, as already stated, is made in sections, which fit end to end, and the Figs. 1, 2, and 3 show one of these sections complete, 40 with a portion of each of the two adjacent sections.

a is a trough-like casting of iron, suitably strengthened, as the drawings indicate, by internal flanges. This is laid in the position usually occupied by the curbstone, and the sections 45 are similarly laid in series end to end.

a' *a'* are holes in the ends of the casting *a*.

b is a cast-plate, serving as a cover to the

part *a*. It is roughened on the face to give good foothold, and on its under side it is provided at one end with perforated lugs *b'* and at the other with hook-like studs *b*².

In laying the curbing the studs *b*² are made to pass through the holes *b'* in the end of the casting *a*; also, to enter the corresponding holes in the next casting and the perforations through the lugs *b'* of its cover. In this way the parts of the curbing become securely locked together. At convenient distances a cover is employed in which the lugs are at *b*²*, and are fastened by a pin at the front of the curb. This cover can then be raised whenever it is desired to obtain access to the cavity within the curb. The remaining covers are also thus set free, so that in succession they may be slid endwise to clear the studs *b*² and then lifted off. The replacing the covers when the wires are suitably arranged is equally easy.

What I claim is—

1. The combination of the sectional troughs open at their tops and ends and the detachable sectional covers interlocking with each other and with the troughs, substantially as and for the purpose hereinbefore set forth.

2. The combination of the open-top troughs *a*, having holes *a'* in offsets or flanges at their open ends, and the covers *b*, provided at their ends with perforated lugs *b'* and hook-like studs *b*², each cover-stud interlocking with the holes in the adjacent ends of two troughs and with the perforated lug of the adjacent cover, substantially as and for the purpose hereinbefore set forth.

3. The combination, with a trough of a street-curb made of trough-sections open at top and ends and fitted with sectional detachable covers, of a cover, *b*, having a lateral lug, *b*²*, passing through an opening at the front of the trough and secured, substantially as and for the purpose hereinbefore set forth.

WILLIAM REDDALL.
